CLAIM

The ornamental design for a towel capelet, as shown and described.

DESCRIPTION

FIG. 1 depicts a front perspective view of a towel capelet. FIG. 2 depicts a back perspective view of a towel capelet. FIG. 3 depicts a front elevational view of a towel capelet. FIG. 4 depicts a back elevational view of a towel capelet. FIG. 5 depicts a left side view of a towel capelet. FIG. 6 depicts a right side view of a towel capelet. FIG. 7 depicts a top side view of a towel capelet. FIG. 8 depicts a bottom side view of a towel capelet. FIG. 9 depicts a front perspective view of a towel capelet showing alternative embodiment of variable length; and, FIG. 10 depicts a front perspective view of a towel capelet showing alternative embodiment of perimeter trim. The broken lines in the drawings show portions of the towel capelet that forms no part of the claimed design.
